GARAGE DOOR HANGER

Arthur L. Clark, Wichita, Kans.

Application June 20, 1938, Serial No. 214,741

2 Claims. (Cl. 20—19)

My invention relates to improvements in garage door hangers, and has for its principal object to move the door vertically and horizontally to an overhead position.

5 A further object of my invention is to provide hangers for a garage door whereby a single track may be employed to carry the upper end of the door, and means to carry each side thereof, said means coacting in their movement to guide the door to an open or closed position.

10 A still further object of my invention is to provide a system of counter balancing weights that will carry the door uniformly from its open to a closed position.

15 A still further object of my invention is to provide an adjustment for the weight cable connections whereby, should the weights exceed the weight of the door, or vice versa, the same may be equalled by the adjustment provided.

20 These and other objects will hereinafter be more fully explained, reference being had to the accompanying drawings forming a part of this specification, and in which like characters will apply to like parts in the different views.

25 Referring to the drawings:

Fig. 1 is an inside perspective view of the garage door and its hangers.

Fig. 2 is a sectional view taken on line 2—2 in Fig. 2.

30 Fig. 3 is an enlarged fragmentary plan view of the adjustable feature carried by the rockable arm.

Fig. 4 is an enlarged view through the top of the door and head jamb illustrating the trolley and 35 arm as a modified arrangement to guide and carry the top of the door.

Fig. 5 is a transverse view of a trolley and hanger, the track being in cross section.

40 My invention herein disclosed relates to a hanging mechanism for a garage door 1, said door as a closing means for the opening of a garage or like structure. The hangers, supporting and conducting said door, consist of an overhead track 2 on which a sleeve 3 slideably engages, functioning 45 as a trolley, carrying the top portion of the door, the sleeve being connected thereto through the medium of a shank 4 that is hingedly connected to a stiffening bar 5, crossing the door at its upper extremity, by which means when the door is 50 opened it is free to slide longitudinally on the said overhead track, the track being preferably cylindrical in cross section to receive the sleeve thereon.

The lower portion of the door is carried by arms 55 6, said arms each being bent at a right angle to

engage on the inside of the door and rockably secured thereto by clips 7, while the other ends of said arms each rockably engage in an apertured hanger 8, said hanger being secured to a post 8' that is vertically positioned, the said posts being the supporting means for the outer ends of their respective beams 9, the other ends of which are secured to the wall of the garage adjacent the upper end of the door, and the said beams each have sheaves 10 and 11 trunnioned on the inside 10 thereof, and upon which cables 12 and 13 will engage. The said cables each have a weight 14 and 15 respectively secured to their corresponding ends. The other ends as at 14' and 15' are secured to an apertured bar 16 that is attached to 15 the upper side of arm 6, by means later described, the apertures as at 17 being spaced therealong, and in which cables are secured selectively, the position of which is governed by the gravity action of the weights to counterbalance the door, 20 that is to say should the weights exceed that of the door the connection of the cables should be positioned selectively in apertures spaced from the door and vice versa should the door exceed the gravity action of the weights.

25 To secure the door in its closed position, I have arranged a lock consisting of a bolt 18 that is spring tensioned in its housing 19, the upper end of the bolt engaging in the keeper 20 in the head jamb of the door. To disengage the lock there is 30 a connecting rod 21 attached to the lower end of the bolt and to a crank 22 that turns with a shank 23, to which is secured a handle 24 as turning means therefor, moving the bolt to unlock the door, after which the upper portion of 35 the door may be moved inward as starting means to open the same in a horizontal position as shown by dotted lines A in Fig. 2, and in its movement to such position, arm 6, as attached to the door, will follow the dotted line B to its vertical position as shown by dotted lines C. When so positioned, the weights 14 will drop downward as shown by dotted lines D in Fig. 2 while weights 15 will drop to the position as shown by dotted lines E.

40 To close the door, there is placed at the under side thereof, medial of its width, an arm 25 hingedly connected at its upper end as at 26, and being tensioned to engage against the door by a leaf spring 27 that is positioned under the 50 hinge bolt, while the outer ends thereof engage against the wings F of the hinge, by which means the door is moved from its horizontal plane to a closed position. As a convenient means to rock the arm downward, there is placed at the free 55

end thereof a drop cord 28, as shown in Fig. 2, said cord extending downward within reach.

In Figs. 4 and 5 is shown a modified guiding means for the top of the door which is accomplished through the medium of a trolley 29, the wheels of which roll on the oppositely disposed flanges 30 of a T-iron, the leg 31 of which extends upward as stiffening means for the trolley track, said trolley being hingedly connected 10 at the top of the door as at G to permit rocking movement when the door is being opened and closed.

In Figs. 1 and 2 is shown one hookup for the weights as an example for description; for instance, to combine all four of the weights it is found that they exceed the weight of the door, and the said weights will counteract the purchase of each other, and at all times will tend to coact to produce a constant resultant tension along the 20 door line of travel from its vertical to a horizontal plane; in other words, when arm 6 is rocked upward so that the contact point of cables 12 and 13 are aligned between the upper periphery of the sheave 11 and the point where the arm is pivotally connected to the post weight 15 is neutral, while the connecting point of weight 14 has approached its maximum purchase to move the door to a horizontal position, and when so positioned the said weight 14 overbalances 25 the door closing tendency of weight 15 so that the door will remain against retraction. However, the said weight 15 will assist in retraction movement of the door and also assist weight 14 as it loses its purchase as the door approaches its 30 vertical position, at which time, when the door is closed, weight 14 has lost some of its purchase due to the angle of its respective cable 12 as connected to the arm a spaced distance from the door, but counteracted by the lesser weight 15 through the semidirect pull of its cable 13, the connecting point of which is spaced outward 35 from the connecting point of the other cable.

Inasmuch as doors vary in weight with respect to weights purported to balance such doors, and 40 for such reason previously described, the free end of the cables are attached in their respective apertures 17 selectively, and for a closer adjustment, the said bar 16 is slideably arranged on arm 6 and secured thereto by clamps 16' at a selected position along said arm without seriously 45 impairing the purchase of either weight when the bar is rocked to a vertical position. The adjustment must be such that the door will remain in its closed position and retained in its hori-

zontal position undisturbed except when manually moved.

While I have shown and described a door having a single track to carry its upper extremity, the same may be modified by the application of a plurality of tracks as the door increases in width; and, the said weights being positioned in pairs that are positioned at each side of the door, the same may be varied by the use of appropriate sheave mountings, whereby the weights may be placed at one side of the door with equal function to that disclosed herein, and pockets may be arranged in which the weights will move vertically, and such other modifications may be made as lie within the scope of the appended 15 claims.

Having fully described my invention what I claim as new and desire to secure by Letters Patent is:

1. In garage door hangers, hangers of the class 20 described, an arm, one end of which is rockably connected adjacent each side edge of the door, a post spaced from the door and to which the other end of said arm is pivotally connected, on which connection the arm will rock carrying the 25 door therewith, means to secure the post vertically, a pair of sheaves trunnioned on said means and being spaced apart, a cable to engage on each sheave, one end of each cable being secured to the arm adjacent the door and a weight connected to the other end of each cable as retaining 30 means for the door at its rocked position, and a track horizontally positioned as guiding means for the door as said door is rocked from a vertical to a horizontal position. 35

2. In garage door hangers, hangers of the class 40 described, an arm, one end of which is rockably connected adjacent each side edge of the door, a post spaced from the door and to which the other end of said arm is rockably connected, on 45 which connection the arm will rock, carrying the door therewith, means to secure the post vertically, a pair of sheaves trunnioned on said means and being spaced apart, a cable to engage on each sheave, one end of each cable adjustably secured to the arm adjacent the door, a weight 50 connected to the other end of each cable as retaining means for the door at its rocked position, a trolley hingedly connected to the top of the door, and a track on which the trolley will engage as guiding means for the door in its rocking movement.

ARTHUR L. CLARK.
